DESIGN FOR A SHOE

Samuel J. Meyer, New York, N. Y.

Application January 15, 1936, Serial No. 60,590

Term of patent 3½ years

To all whom it may concern:

Be it known that I, Samuel J. Meyer, a citizen of the United States of America, residing in the city of New York, county of New York, and State of New York, have invented a new, original, and ornamental Design for a Shoe, of which the following is a specification, reference being had to the accompanying drawing, forming part thereof,

I claim:

The ornamental design for a shoe substantially as shown.

SAMUEL J. MEYER.
